UNITED STATES PATENT OFFICE.

JAMES A. CAREY, OF NEW YORK, N. Y., ASSIGNOR TO STANDARD STOKER COMPANY, INCORPORATED, OF NEW YORK, N. Y., A CORPORATION OF DELAWARE.

STOKER.

Application filed June 28, 1921. Serial No. 480,985.

To all whom it may concern:

Be it known that I, JAMES A. CAREY, a citizen of the United States, residing at New York, in the county and State of New York, have invented certain new and useful Improvements in Stokers, of which the following is a full, clear, and exact description.

This invention relates to improvements in stokers, and more particularly to improvements in the stoker shown in the patents to Williams Nos. 1,118,985 and 1,099,956 and in my copending application Serial No. 335,100. In my copending application I have improved the Williams stoker by the elimination of gearing and connecting shafting to drive the conveyor elements of the stoker. Drive to these elements is attained through a worm wheel and worm gear mounted upon a shaft extending to an engine wheel runs at comparatively high speed.

The present invention has for its object the provision of a drive which will permit the driving engine to be of the low speed type and to be so mounted as to drive the driving gear of the conveyor through the medium of a single idler gear, thereby eliminating shafting and extra gearing.

A further object resides in the provision of a drive of such character that a compact arrangement of engine and conveyor is secured. Preferably both units may be mounted upon the same supporting structure.

Further objects and advantages will be pointed out in more detail in the accompanying specification and claims and shown in the drawings, in which:—

Fig. 1 shows a substantially central section of the stoker with certain parts in outside elevational view to show the driving connection.

Fig. 2 shows a cross sectional view through main conveyor driving gear and shows a side elevation of the driving engine and associated parts.

Fig. 3 shows a top view of certain details of the driving connections.

Fig. 4 shows a detail view of the mounting for the intermediate gear.

The stoker which is illustrated in Fig. 1 is fully described in my copending applica-

tion heretofore referred to. Reference may be had to this application for an understanding of the details of construction.

It is here sufficient to state that the vertical conveyor screw 7 receives its drive through bevel gears 8 from a horizontal conveyor screw 10. The vertical conveyor screw is suitably mounted in a passaged structure 9. The horizontal conveyor screw 10 receives its drive from a gear 11 which forms a part of the screw. This gear, as well as the screw itself, is mounted in a passaged structure comprising parts 12, 13, 14, which parts are suitably fastened to a base 15, as best shown in Fig. 2. The gear 11 is of the spur type instead of having worm wheel teeth thereon as in my prior construction.

E represents the driving engine. This may be of any desired type, but, for economy and reliability in operation and efficiency in upkeep, I prefer to utilize a slow speed reciprocating steam engine having a plurality of cylinders and with their pistons driving a crank shaft by means of the connecting rods 16. These rods co-operate with suitable crank pins on crank discs 17, and intermediate the discs and driven in unison therewith upon their rotation is a spur gear 18. This gear on the engine crank shaft will hereinafter be referred to as an engine gear.

The engine E is provided with a crank case 19—20 split longitudinally, as shown in Fig. 2, and the entire engine assembly or unit is fastened to a sub-base 21 which is attached in any suitable manner to the base 15.

Preferably attached to the lower half of the crank case is a pair of arms 22 (see Figs. 1 and 4). These arms form a bracket to suitably support a pin 23 which carries a spur gear 24 hereafter called an intermediate gear. This gear 24 meshes with gear 18 and gear 11 and drives the latter upon rotation of the former. The engine crank case and housing 13 are suitably apertured to permit the entry of gear 24 into meshing relation with the engine gear and the conveyor drive gear.

The arrangement described provides an exceedingly compact disposition of the parts and minimizes the number of parts which

require lubrication and care. Furthermore, the engine and speed reducing gearing may be removed as a unit for repair or substitution of a new unit.

What I claim is:—

1. In a conveyor for stokers, in combination, a conveyor screw, a passaged structure therefor, a support for said passaged structure, a spur gear mounted in a section of said passaged structure and connected to said conveyor screw for driving the same, a driving engine having a driving gear train mounted thereon and forming therewith a unitary driving element, said gear train including a gear on the engine crank shaft and a spur gear meshing in driving relation with said screw spur gear, a casing for said engine and gear train and a support for said unitary driving element carried by the support for said passaged structure, said unitary driving element being removable from its support and replaceable thereon as a unit from and to driving relation respectively with said screw spur gear. 70
2. In a conveyor for stokers, in combination, a horizontal conveyor screw, a lifting conveyor screw driven from said horizontal screw, passaged structures for said conveyor screws, supports for said passaged structures, a spur gear connected to the horizontal conveyor screw intermediate its ends, forming a section of the horizontal passaged structure and forming also a bearing support for the conveyor screw, a driving engine having a driving gear train mounted thereon and forming therewith a unitary driving element, said gear train including a gear on the engine crank shaft and a spur gear meshing in driving relation with said screw spur gear, a casing for said engine and gear train, and a support for said unitary driving element carried by the support for one of said passaged structures, said unitary driving element being removable from said support and replaceable thereon as a unit from and to driving relation respectively with said screw spur gear. 75
3. In a conveyor for stokers, in combination, a conveyor screw, a passaged structure therefor, a support for said passaged structure, a spur gear mounted in a section of the passaged structure and connected to said conveyor screw for driving the same, a driving engine having a driving gear train mounted thereon and forming therewith a unitary driving element, a casing for said engine and gear train, supporting arms carried by said engine casing, said gear train including a gear on the engine crank shaft and an intermediate spur gear rotatably carried by said supporting arms and in permanent mesh with said crank shaft gear and in driving relation with said screw spur gear when the driving engine is mounted in operating position, a support for said unitary driving element attached to one of said passaged structure supports, said unitary driving element being removable from its support and replaceable thereon as a unit from and to driving relation respectively with said screw spur gear. 80
4. In a conveyor for stokers, in combination, a horizontal conveyor screw, a lifting conveyor screw driven from said horizontal screw, a passaged structure for said conveyor screw, supports for said passaged structures, a spur gear connected to the horizontal conveyor screw intermediate its ends, forming a section of the horizontal passaged structure and forming also a bearing support for the conveyor screw, a driving engine having a driving gear train mounted thereon and forming therewith a unitary driving element, a casing for said engine and gear train, supporting arms carried by said engine casing, said gear train including a gear on the engine crank shaft and an intermediate spur gear rotatably carried by said supporting arms and in permanent mesh with said crank shaft gear and in driving relation with said screw spur gear when the driving engine is mounted in operating position, a support for said unitary driving element attached to one of said passaged structure supports, said unitary driving element being removable from its support and replaceable thereon as a unit from and to driving relation respectively with said screw spur gear. 85
5. The combination with a locomotive and tender, a conveyor adapted to carry coal from the tender to the locomotive fire box, comprising a horizontal screw and a lifting screw driven from said horizontal screw, a passaged structure for said screws, a support on said locomotive for the forward portion of said passaged structure and means for driving said screws comprising a spur gear connected to the horizontal conveyor screw intermediate its ends, forming a section of the passaged structure and forming a bearing support for the conveyor screw, a driving engine having a driving train mounted thereon and forming therewith a unitary driving element, said driving element being accessible and removably carried below the deck of said locomotive by said support. 90
6. The combination with a locomotive and tender, a conveyor adapted to carry coal from the tender to the locomotive fire box comprising a horizontal screw and a lifting screw driven from said horizontal screw, a passaged structure for said screws extending beneath the deck of said locomotive, a support on said locomotive for the forward portion of said passaged structure and means for driving said screws comprising a spur gear connected to the horizontal conveyor screw intermediate its ends, forming 95

a section of the passaged structure and forming a bearing support for the conveyor screw and a unitary removable accessible driving element for said gear carried by said support beneath the cab deck at one side of said passaged structure, said element comprising a casing, a reciprocating

engine carried by said casing and a gear train connected to the crank shaft of said engine and mounted on said casing in the plane of said spur gear.

In testimony whereof I hereto affix my signature.

JAMES A. CAREY.
